Ryan Schneider; Chris Davis(57) CLAIM

The ornamental design for a hard skin removal device, as shown and described.

DESCRIPTION

FIG. 1 is a perspective view of our new design for a hard skin removal device;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines are included for the purpose of illustrating a portion of the hard skin removal device that forms no part of the claimed design.
